[57] CLAIM

The ornamental design for a saw sharpener or the like, as shown and described.

DESCRIPTION

FIG. 1 is a perspective view of the saw sharpener or the like showing our new design;

FIG. 2 is a side view of the saw sharpener of FIG. 1; FIG. 3 is a top view of the saw sharpener of FIG. 1; FIG. 4 is an opposite side view of the saw sharpener of FIG. 1;

FIG. 5 is a cross-sectional view of the saw sharpener of FIG. 2 viewed along the line 5—5;

FIG. 6 is a cross-sectional view of the saw sharpener of FIG. 2 taken along the line 6—6; and

FIG. 7 is a cross-sectional view of the saw sharpener of FIG. 2 taken along the line 7—7.

FIG. 1
